UNITED STATES PATENT OFFICE.

WILLIAM RILEY, OF NEW YORK, N. Y., ASSIGNOR TO HIMSELF AND
PATRICK H. GILLEN, OF SAME PLACE.

TOBACCO-BOX.

SPECIFICATION forming part of Letters Patent No. 275,944, dated April 17, 1883.

Application filed July 21, 1882. (Model.)

To all whom it may concern:

Be it known that I, WILLIAM RILEY, of the city, county, and State of New York, have invented a new and Improved Combination Tobacco-Box, of which the following is a full, clear, and exact description.

My invention consists principally of a combined tobacco and match box of special construction.

Reference is to be had to the accompanying drawings, forming part of this specification, in which similar letters of reference indicate corresponding parts in all the figures.

Figures 1 and 2 are perspective views of my new and improved combination tobacco-box.

A represents the body of the tobacco-box, which is formed with the notched upright catch b and upright plate a; and B represents the cover of the tobacco-box, which is provided with the match-box C and a dice-box, D.

The back of the body A of the tobacco-box is provided with the mirror F, as shown in

Fig. 2. The upright plate a is by preference secured to the body A, near one end, and the match-box C is secured to the cover B at one end, as clearly shown in Fig. 1, so that when the cover is closed the plate a will close the match-box, as will be clearly understood from the said figure.

Having thus fully described my invention, I claim as new and desire to secure by Letters Patent—

A tobacco-box having a match-box at the front end, arranged along one side of its top, and the vertical plate a, rising from the end of body, opposite to the match-box, whereby in lifting the front of cover both the tobacco and the matches are simultaneously brought to view and within reach, as described.

WILLIAM RILEY.
